UNITED STATES PATENT OFFICE.

HIRAM S. HEARN, OF DENVER, COLORADO.

TRANSMISSION SWITCH.

1,404,609.

Specification of Letters Patent. Patented Jan. 24, 1922.

Application filed January 9, 1920. Serial No. 350,412.

To all whom it may concern:

Be it known that I, HIRAM S. HEARN, a citizen of the United States, residing at Denver, in the county of Denver and State 5 of Colorado, have invented new and useful Improvements in Transmission Switches, of which the following is a specification.

The object of the invention is to provide a relatively inexpensive and effective switch 10 adapted for use in connection with transmission circuits and power systems for simultaneously opening and closing a plurality of circuits including those of high voltage of the multiple phase type under 15 such conditions as to eliminate arcing and the shunting or jumping of the same so as to cause a single phase current to pass through multiple phase machinery or the like or the reverse thereof to the injury of 20 such machinery, and otherwise to provide the switch mechanism wherein the capacity so far as handling current is concerned is limited only by the strength of the insulator or insulating units used at the switch 25 terminals.

With these and related objects in view as will appear in the course of the following description of a preferred embodiment of the invention, the same consists in a construction 30 and combination of parts as shown in the accompanying drawing, it being understood that changes in form, proportion and details may be resorted to within the scope of the appended claims without departing from the principles involved.

In the drawings:

Figures 1 and 2 are respectively plan and side views of a battery of switches arranged in independent transmission lines or circuits 40 and adapted for simultaneous operation through the movement of a common operating lever or unit.

Figure 3 is a side view of one of the switch units, one of the terminals being 45 shown in section to show more clearly the relation between the parts thereof.

A plurality of switch units A, B, C, may be arranged upon a single support consisting for example of the uprights 30 connected by 50 the longitudinal beams 31, arranged as shown in parallel spaced relation, and suitably bolted to the uprights as shown at 32 and braced as at 33, one of the uprights being utilized as a support for upper and 55 lower brackets 34 and 35 for supporting an operating rod 36 to which is connected the

operating handle or lever 37. The latter is preferably of fiber or other insulating material and should be grasped by the operator only when standing upon a suitably insulated platform or table (not shown), said lever normally being locked in position so that it may not be subject to accidental or surreptitious movement, as by providing it with a locking ring or eye 38 for registration 60 with a similar ring or eye 39 on the bracket 35 for engagement by a padlock 40.

Transversely connecting and terminally extending beyond the longitudinal beams 31 are cross bars 41 and 42, of which the latter 70 are preferably channel iron, secured as by bolts 43 to said longitudinal beams and provided at their extremities with registering bearings 44 and 45 for the reception of the insulator pins 46 which are thus revolubly 75 mounted in the cross bars and are arranged in transversely opposite positions to form the support for the complementary elements of the respective switch units. Said insulator pins are preferably provided with collars 46^a to bear upon the channel bars 42 and are cemented at their upper ends to the insulators 47 which they respectively support.

At their lower extremities the insulator 85 pins are reduced and shaped to form cross sectionally angular or irregular portions for engagement by correspondingly formed openings in the hubs of the bell crank levers 50, of which the arms 51, which are preferably formed separately from the arms 52 are connected by links 53 with arms 54 on the transversely opposite insulator pin while the arms 52 are connected in series by links 55. The terminal bell crank lever of the 90 series is connected by a link 56 with an arm 57 carried by the operating rod 36 to the end that by means of the operating lever or handle 37 all of the insulator pins may be turned in a common direction to either close 100 or open the several circuits controlled by the switch units A, B and C, of which obviously any desired number may be employed in a single apparatus for simultaneous actuation.

Carried by each insulator pin and secured 105 to the insulator supported thereby is a metallic cap 58 consisting of the separate members 59 and 60, adjustably secured together by bolts 61 and combining to form the clamping ring 62 which embraces the insulator in a seat formed near the upper end thereof, and a table 64 having a central

threaded opening 65 for engagement by the threaded end of a cap screw 66 which extends downwardly through a swivel joint 67. Also supported by and resting upon the 5 table of the cap is a switch blade 68 adapted to cooperate with the complementary blade carried by the transversely opposite element of the same unit to close the circuit through the switch, the adjacent free ends of said 10 blades being adapted to overlap in order to form the contact, and said overlapping portions preferably being beveled to form contact surfaces, said blades being of yielding or resilient material to provide for an efficient 15 electrical contact, and one of the blades of each pair preferably being spaced slightly from its supporting cap by means of a distance or spacing plate 70 as shown at the right in Figure 3 so that in closing the 20 switch the blade which rests upon said distance or spacing plate will with certainty pass over and overlap the complementary blade carried by the opposite element of the switch unit.

25 Connection with these blades of the line wire terminals, is effected through the swivel joints 67 having the outer socket arms 71 with which the lines 72 are connected, and the inner socket arm 73 from which extends 30 the braid proper pig-tails 74 secured as at 75 to said blades. The cap screws 66 serve to hold said blades in place upon the tables 64, by passing through suitable openings 76 therein, the cap screw of one member or element 35 of each switch unit also passing through an opening in the distance or spacing plate 70 and the heads of said cap screws bearing upon washers 79 which rest upon the upper ends of the swivel joints.

40 As so far described an efficient switch construction has been provided, wherein the opening and closing of the several circuits controlled respectively by the switch units may be effected simultaneously. To the end 45 that the possibility of a shunt or cross over is reduced, it is desirable to minimize this possibility, particularly in dealing with current of a voltage of 11,000 or more, and to this end the elements of each switch unit are 50 provided with auxiliary switch members or circuit breaker arms or horns, preferably formed of hard brass rods, having their outer or fast terminals which are laterally offset as shown at 80 secured to the blades 68 by 55 means of clamps 81, held in place by bolts 82, said auxiliary switch members having resilient or spring arms 83 which lie in contact with the upper surfaces of the switch blades 68 respectively, and primarily serve as a means 60 of fortifying the contact between the overlapping or contact surfaces of said blades, as will be particularly obvious by reference to Figure 3 of the drawings wherein, the switch being closed, the inner end of one of the 65 auxiliary switch arms rest upon the upper or overlapping terminal of the engaged blade and is separated from the blade upon which it normally bears by the interposition of the said terminal of the overlapping blade member. These auxiliary switch members however are provided with terminal contact elements consisting of angularly disposed arms 84 and 85, the former of which are extended transversely and obliquely inward or toward the opposite switch member in a plane parallel 70 with the switch blade while the latter, springing from the outer extremities of the arms 84 incline upwardly and rearwardly in relation to the direction of closing movement of the switch member and pass over the vertical plane of said switch members as shown clearly. These contacting elements of the auxiliary switch members extend beyond the plane of possible contact of the switch blade and have a yielding or spring tendency 80 toward each other or in a direction parallel with the length of the switch blades and hence across the path of movement of the switch blade to the end that while such contact elements of the auxiliary switch elements remain in contact and in current conveying relation until after a complete separation of the switch blade has been effected and points of engagement which are on the upwardly divergent arms 85 gradually approach the angles formed by the juncture of said arms 85 with the transversely extending arms 84, and when the disengagement of said auxiliary contact elements occurs, said elements spring across each other's paths or 90 planes of movement in a direction transverse to the path of movement to produce an effective circuit breaker which in practice will avoid the possibility of an arc at that point. Thus the auxiliary switch members may be 95 described as having contact elements of which the circuit closing shown is in excess of that of the main switch elements represented by the blade, said contact elements having contact areas which are moved beyond the plane 100 of the main switch members as the latter are moved to open the circuit, and are yieldingly impelled toward each other while in contact so that upon disengagement or release, said contact elements cross each other's paths in 105 reverse directions to insure the abrupt or instantaneous formation of a circuit opening gap. Obviously the stress of the spring or yielding tendency of the contact faces or elements of the auxiliary switch members may 110 be varied in the field by manipulating the arms 84 and 85.

115 From the foregoing description it will be obvious that the arrangement of the contacting surfaces of the switch blades in horizontal overlapping planes will prevent the access of water to the contacting faces, tending to interfere with the progress of the current and as a further insulating precaution for the protection of the operator the switch op- 120

125 130

erating rod 36 is preferably provided with an insulating section 86 having reduced extremities 87 fitted in the tubular rod members, and while the swivel joint 67 and contact blades 68 should be of copper and the auxiliary switch members or horns of hard brass, the other metallic parts of the apparatus may be galvanized as a means of preventing the formation of rust.

10 What is claimed is:

1. A switch apparatus comprising a supporting frame, a plurality of spaced switch units each having an insulator pin revolvably mounted in the frame and carrying insulator elements, switch arms carried by said pins above said insulator elements for simultaneous movement in opposite directions, said switch members having their free ends formed for engagement, line wire connections with the switch members of each unit, angularly extending arms carried by the pins

of each unit, links connecting the arms of each unit, a second angularly extending lever arm carried by one pin of each unit, and a longitudinally movable rod connected with 25 said last named lever arms whereby to effect simultaneous movement of the switch members of all the units.

2. A switch apparatus of the character described comprising a support, vertically extending pins carried by the support and carrying insulator members, switch blades carried by said pins, and means for rotating the pins in the same direction whereby to move the switch blades toward or from each 35 other, the meeting ends of the switch blades being formed with laterally extending inclined resilient portions adapted to conformingly engage.

In testimony whereof I affix my signature. 40

HIRAM S. HEARN.
